(No Model.)

D. W. CASE.
SECTIONAL BOAT.

No. 274,171.

Patented Mar. 20, 1883.

Attest:

A. Barthel

M. J. Drury

Inventor:

Dudley W. Case

by his Atty Thos. D. Sprague,

UNITED STATES PATENT OFFICE.

DUDLEY W. CASE, OF BAY CITY, MICHIGAN.

SECTIONAL BOAT.

SPECIFICATION forming part of Letters Patent No. 274,171, dated March 20, 1883.

Application filed December 8, 1882. (No model.)

To all whom it may concern :

Be it known that I, DUDLEY W. CASE, of Bay City, in the county of Bay and State of Michigan, have invented new and useful Improvements in Steam-Vessels; and I do hereby declare that the following is a full, clear, and exact description thereof, reference being had to the accompanying drawings, which form a part of this specification.

10 This invention relates to certain new and useful improvements in the construction of that class of vessels which are propelled by steam; and the invention consists in constructing a vessel with comparatively open midships, while the bow and stern sections are water-tight and separated from the open midship section by water-tight bulk-heads, for the more ready convenience in loading, transporting, and discharging logs and timber, such as is now usually rafted from point to point.

15 It is usual in moving large masses of logs or timber from the place of production to the point of consumption to make such logs or timber up into rafts, which are towed by means of tugs—a process accompanied by great risks of loss and at a large expenditure of time; and the object of my invention is to construct a vessel which carries her own means of steam propulsion, so constructed that the rear section 20 may be detached in whole or in part from the midship section, and provided with appliances by means of which such sections are secured together, adapted for loading the logs into the open midship sections, and provided 25 with means for detaching the stern section for the ready discharge of the logs.

30 The invention consists in the peculiar construction of the parts and their various combinations and operation, as more fully herein-after described.

35 Figure 1 is a side elevation of my improved steamboat. Fig. 2 is a top plan. Fig. 3 is a midship cross-section, and Fig. 4 is a sectional detail, in elevation, of the front and midship sections detached from the stern section.

40 In the accompanying drawings, which form a part of this specification, A represents the bow section of a boat, and B the open midship section, consisting of a keel, *a*, and floor, *b*, 45 and the sides *c*, which are built up from the floor by means of rectangular timbers, laid one upon the other and secured in any convenient

way, by means of which the sides are made concave. Of course from the point *d* to the cut-water *e*, or extreme front of bow, these 55 sides are made to conform by bending or otherwise to the proper shape to form the bow. The bow section from *d* to *e* is caulked and made water-tight and decked over tightly to form a perfectly water-tight compartment, the rear 60 end of which is formed by the tight bulk-head C. The midship section, which extends from *d* to *f*, is made of timber, as I have already described, not decked over or caulked, so that water may leak freely through the same, and the 65 timbers used for the bow section and the forward part of the midship section are preferably of a lighter gravity than the timbers used to form the rear portion of the midship section, such timbers being (to obtain the necessary 70 length of midship section) in sections secured together in a manner well known to vessel-builders, and some of these timbers project beyond the rear line of such midship section, as shown at D.

75 E is the stern section, built in the ordinary manner, and provided with a water-tight bulk-head, F, by which the forward end of such stern section is closed. This stern section is fitted up with the usual boiler, engine, and 80 means of propulsion, with coal-bunkers, pilot-house, and is also provided with the necessary winches to successfully operate the vessel.

85 In Fig. 1 it will be noticed that the overhanging section D of the midship section rests against the under side of the rail G on each side of the stern section, where it is secured by means of the winches and chains H; or 90 these two sections may be secured together in any other desired manner which will allow them to be readily detached when required.

95 As before remarked, the midship section is of any desired length, and the manner of building it up is plainly shown in Figs. 1 and 3, where, to obtain such desired length, various lengths of timbers to form the walls of this section are spliced together in a manner well known to ship and bridge builders. Upon the top rail of the midship section is supported an overhanging frame-work, I, to which are secured the pulleys J, over which run the chains K, which lead to the winches L upon the deck of the stern section, and which may be operated by steam, if preferred. The other ends 100

of these chains are secured to the top of the vessel's sides, as at *g*. The design of this arrangement is to unwind the chains from the winches to allow them to fall in loops, as shown 5 in Fig. 1, into the water, on one or both sides of the vessel, such loops to engage with the logs, one of which is shown in Fig. 3 engaged in such loops, and after such engagement is had, by winding the chains upon the winches, 10 the logs are elevated over the sides of the midship section and dropped into the hold, as shown in Fig. 3.

The bow section is provided with the pump *M*, by means of which water accidentally admitted 15 may be thrown out, and also for throwing out water which may be purposely admitted, for the purpose of counteracting, when necessary, the buoyancy of the bow.

The vessel having been loaded and in the 20 condition shown in Figs. 1 and 2, on reaching her destination to be discharged, the latter is done by disengaging the midship section from the stern section, and the rear end of the midship section, being heavier, (owing to the heavier 25 gravity of the timber of which it is constructed,) on being so disconnected from the stern section, will sink to a greater depth in the water, allowing the logs to slide down the inclined plane and be floated out. Of course, 30 during this operation, there should be no water in the bow section, as its greater buoyancy then has a tendency to give a greater inclination to the floor of the midship section to facilitate the unloading process. After being 35 unloaded the stern section is again brought into place and secured.

I am aware of Patents Nos. 47,501, granted

to E. Turner, April 25, 1865, for a floating dock, and 232,740, granted to T. McCosker, September 28, 1880, for an oyster-float, and make no 40 claim thereto.

What I claim as my invention, and desire to secure by Letters Patent, is—

1. A vessel carrying her own means of propulsion, and consisting of a water-tight section, substantially in the form of a vessel's bow, an open midship section through which the water may freely flow, and a water-tight section in the form of a vessel's stern, detachably secured to the open rear end of the said 45 midship section, substantially as and for the purposes described.

2. A vessel consisting of a tight section in the form of a vessel's bow, an open midship section, and a tight section in the form of a 55 vessel's stern, in combination with means for detachably securing said stern section to the open midship section, substantially as and for the purposes specified.

3. In combination with a tight bow section 60 of a vessel and a detachable tight stern section thereof, an open midship section, the rear end of which is made heavier than the front, substantially as and for the purposes set forth.

4. In combination with a vessel constructed 65 substantially as described, an overhanging frame supported on top of the open midship section, provided with means, substantially as described, for loading said section, as specified.

DUDLEY W. CASE.
